DRAFT CHECK

William Serrick, Fairbanks, Alaska, assignor to
 Orval W. Holmes, Fairbanks, Territory of
 Alaska

Application January 12, 1940, Serial No. 313,611

3 Claims. (Cl. 20—67)

This invention relates to a draft check for doors to prevent air from passing under a door when in a closed position, and has for the primary object the provision of an efficient and inexpensive device of this character which may be readily installed on a door and which will automatically move to tightly engage with the door sill or the floor when the door moves into fully closed position to exclude air from under the door and which will automatically move upwardly away from the floor as the door begins to move toward an open position to prevent the device from dragging on the floor and interfering with the opening of the door and scratching or otherwise damaging the floor.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a fragmentary side elevation showing a portion of a door and door frame with the check applied to the door.

Figure 2 is a sectional view taken on the line 2—2 of Figure 1.

Figure 3 is a view showing the device associated with a door frame with the door omitted.

Figure 4 is a sectional view taken on the line 4—4 of Figure 3, showing the device on the door and in engagement with the floor to exclude air from under the door.

Figure 5 is a view similar to Figure 4 showing the device on the door when the latter is in an open position so that said device is free of the floor.

Figure 6 is a fragmentary perspective view illustrating a portion of the draft check.

Figure 7 is a fragmentary sectional view showing the operating cam of the device engaging with a grooved portion formed in the door frame for bringing about actuation of the device into engagement with the floor when the door is closed.

Referring in detail to the drawings, the numeral 5 indicates a fragmentary portion of a door frame and 6 a fragmentary portion of a door. In adapting the present invention for use on the door and in connection with the door frame the latter has cut or formed therein a cut-away portion or pocket 7 to form or provide a camming wall for a cam element 8 acting as an operating medium for the present invention.

The check is indicated in entirety by the char-

acter 9 and consists primarily of outer and inner elongated plates 10 and 11 arranged to have telescopic relation with each other and are arcuately curved transversely. The outer plate 10 at one edge has integral therewith an attaching flange 12 provided with a series of slots 13 to receive fasteners such as screws or the like, as shown at 14, for adjustably securing the check on the door 6.

It is to be understood that the check 9 when adapted to the door extends for the full width thereof and the inner plate of said check is provided with slots 15 through which reduced end portions 16 of supporting brackets 17 extend.

The reduced portions 16 extend through the outer plate 10 and are headed or riveted, as shown at 18. The brackets 17 form journals for an operating rod 19 on which is formed arms or extensions 20 to engage with lips 21 struck from the inner plate. The inner plate 11 is fitted between the brackets 17 and the outer plate 10 and retained in this position by the reduced end portions 16 and their headed ends 18. This construction will permit the inner plate to have sliding relation with the outer plate so that when the operating rod 19 is rotated in one direction the inner plate will be moved downwardly to contact the floor and its floor-contacting edge is equipped with a cushion strip 22 which when in engagement with the floor will effect an efficient seal therewith and will prevent marring or damaging of the floor by the device.

Leaf springs 23 are carried by the brackets 17 and the ends thereof are attached to lips 24 formed on the inner plate and act to normally support the inner plate in an elevated position away from the floor so that the door in opening and closing will not be interfered with by the present invention dragging upon or scraping the floor.

The operating shaft 19 has the cam element 8 secured to one end which operates in aligned notches 25 provided in the inner and outer plates at one end thereof. When the door is open and the inner plate supported in an elevated position by the springs the cam-shaped operating element 8 protrudes through the notches 25 so that on the door reaching a closed position it will have engaged with a wall of the pocket 7 and imparted rotation to the shaft 19 to move the inner plate 11 downwardly so that the strip 22 thereof tightly engages with the floor and thereby effectively prevents the passing of air under the door. As soon as the door starts away from a closed position the springs immediately act to

- move or slide the inner plate upwardly, consequently permitting the door to swing freely without the device dragging on the floor and interfering with the opening or closing of the door.
- 5 5 A device of the character shown and described can be readily installed on any door by anyone unskilled in the art and will in no way interfere with the normal opening and closing of the door but will provide an effective draft check to prevent air from passing under the door when the latter is in a fully closed position.

It is believed that the foregoing description, when taken in connection with the drawings, will fully set forth the construction and advantages 10 of this invention to those skilled in the art to which such a device relates, so that further detailed description will not be required.

Having thus described my invention, what I claim is:

- 20 1. In a draft check for doors, inner and outer plates having telescopic relation and transversely curved, means for adjustably connecting the outer plate to a door, brackets having reduced ends riveted on the outer plate and said inner plate having slots to receive the reduced ends of the brackets for slidably connecting the inner plate to the outer plate, a sealing strip carried by the inner plate, means urging the inner plate away from the floor, and means carried by the 25 brackets and connected to the inner plate for automatically moving said inner plate into engagement with the floor to effect a seal thereon with on the door assuming a closed position.

2. In a draft check for doors, inner and outer plates having telescopic relation and transversely

curved, means for adjustably connecting the outer plate to a door, brackets having reduced ends riveted on the outer plate and said inner plate having slots to receive the reduced ends of the brackets for slidably connecting the inner plate to the outer plate, a sealing strip carried by the inner plate, leaf springs secured to said brackets and the inner plate for urging the latter away from the floor, an operating rod journaled in said bracket, means connecting said operating rod to the inner plate, and means carried by said operating rod to engage with the door frame on the door moving into closed position to effect movement of the inner plate in the direction of and into contact with the floor.

- 15 3. In a draft check for doors, inner and outer plates having telescopic relation and transversely curved, means for adjustably connecting the outer plate to a door, brackets having reduced ends riveted on the outer plate and said inner plate having slots to receive the reduced ends of the brackets for slidably connecting the inner plate to the outer plate, a sealing strip carried by the inner plate, leaf springs secured to said brackets and the inner plate for urging the latter 20 away from the floor, an operating rod journaled in said brackets, an extension on said rod, a lip on said inner plate to engage said extension, and a cam-shaped element secured on the operating rod to contact a door frame on the door moving 25 into closed position to rotate the rod and thereby move the inner plate toward and into contact with the floor.

WILLIAM SERRICK. 35
